US00D458757S

(12) **United States Design Patent** (10) Patent No.: **US D458,757 S**
 Dunn et al. (45) Date of Patent: ** Jun. 18, 2002

(54) **TOOTHBRUSH**

(75) Inventors: **Steven B. Dunn**, Beverly Hills; **Zoltan Pavlakovich**, Woodland Hills, both of CA (US)

(73) Assignee: **Munchkin, Inc.**, Van Nuys, CA (US)

(**) Term: **14 Years**

(21) Appl. No.: **29/136,439**

(22) Filed: **Jan. 31, 2001**

(51) LOC (7) Cl. **04-02**

(52) U.S. Cl. **D4/104**

(58) Field of Search D4/101, 104-112, D4/132, 134, 138; 15/143.1, 159.1, 160, 167.1, 167.2, 186, 187, 191.1; 132/308; 601/139, 141

(57) **CLAIM**

The ornamental design for a toothbrush, as shown and described.

DESCRIPTION

FIG. 1 is a perspective view of toothbrush showing our new design;

FIG. 2 is a front elevational view;

FIG. 3 is a rear elevational view;

FIG. 4 is a first side elevational view;

FIG. 5 is a second side elevational view;

FIG. 6 is a top plan view; and,

FIG. 7 is a bottom plan view.

The broken line structure is for illustrative purposes only and forms no part of the claimed design.

1 Claim, 2 Drawing Sheets
